UNITED STATES PATENT OFFICE.

WILLIAM C. SCHULTZE, OF MARENGO, IOWA.

CAR-BRAKE.

SPECIFICATION forming part of Letters Patent No. 258,495, dated May 23, 1882.

Application filed March 31, 1882. (No model.)

To all whom it may concern:

Be it known that I, WILLIAM C. SCHULTZE, of Marengo, in the county of Iowa and State of Iowa, have invented a new and useful Improvement in Automatic Car-Brakes, of which the following is a full, clear, and exact description.

Reference is to be had to the accompanying drawings, forming part of this specification, of which similar letters of reference indicate corresponding parts in all the figures.

Figure 1, Sheet 1, is a sectional side elevation of my improvement, taken through the line *w w*, Fig. 2, and shown as applied to a car-body. Fig. 2, Sheet 1, is a plan view of the same, partly in section, through the line *x x*, Fig. 1. Fig. 3, Sheet 1, is a sectional end elevation of the same, taken through the line *y y*, Fig. 1. Fig. 4, Sheet 2, is a bottom view of the same. Fig. 5, Sheet 2, is a side elevation of the middle part of one of the side-bars enlarged. Fig. 6, Sheet 2, is a plan view of the same. Fig. 7, Sheet 2, is a perspective view of the end parts of the slide-bars, showing an arrangement for starting the bars by hand. Fig. 8, Sheet 2, is a modification of the same. Fig. 9, Sheet 2, is a sectional elevation of an arrangement for returning the slide-bars to their places when released.

The object of this invention is to provide car-brakes constructed in such a manner that the engineer can apply the brakes successively to all the cars of the train, while the cars shall have no other connection than the ordinary coupling.

The invention consists in a car-brake constructed with a friction-wheel attached to a car-axle, and engaging with a friction-wheel journaled in sliding bearing-blocks and provided with gear-wheels meshing into gear-wheels which engage with sliding rack-bars having grooves for raising and lowering the sliding bearing-blocks and grooves for controlling the pawls that engage with ratchet-wheels attached to the friction-wheel-shaft and thus hold the said shaft from being turned back when the sliding bars are released.

The invention further consists in the combination, with the sliding bars and the car-frame, of a chain, spring, piston, and air-tight cylinder, whereby the said slide-bars are drawn

back to a central position when released, as will be hereinafter fully described.

To timbers attached to the base-frame of the car A are bolted two hangers, B, which are slotted to receive the bearing-blocks C, in which revolve the journals of a shaft, D.

To the shaft D is attached a friction-wheel, E, the face of which is thrown into and out of contact with the face of the friction-wheel F by the downward and upward movement of the bearing-blocks C. The friction-wheel F is attached to the inner axle, G, of a car-truck.

To the sides of the friction-wheel E are attached, or upon them are formed, beveled-gear wheels H, the teeth of which, when the friction-wheel E is lowered into contact with the friction-wheel F, mesh into the teeth of the beveled-gear wheels I, pivoted to the cross-bar J, attached to and connecting the lower ends of the hangers B. The teeth of the beveled-gear wheels I also mesh into the teeth of the rack-bars K, formed upon or attached to the lower parts of the inner sides of the bars L, which slide in recesses in the inner sides of the hangers B and bearing-blocks C, and in keepers M attached to the base-frame of the car-body A. The friction of the slide-bars L is lessened by rollers N pivoted to the keepers M, or other suitable supports, and which bear against the upper and lower edges of the said slide-bars L. With this construction, when the friction-wheels E F are in contact, the slide-bars L will be moved by the advance of the car in the opposite direction from that in which the said car is moving.

To the inner side of the lower part of each bearing-block C is attached a pin, O, which, when the slide-bars L are in their central or normal position, rest in a seat, P, at the upper end of the upwardly-inclined inner part of a groove, Q. The lower part of the groove Q is horizontal, and at the outer end of the said lower part is formed an upward curve leading to the outer end of the upper part of the said groove. The upper part of the groove Q is also horizontal, and at its inner end opens into the upper end of the inclined inner part of the said groove.

In a recess in the bar L, above the inner end of the upper part of the groove Q, is pivoted a dog, R, which rests upon the lower side of the

said part of the groove Q, and prevents the pin O, when it leaves its seat P, from entering the upper part of the groove Q, and compels the said pin to pass down into and pass along 5 the lower part of the said groove. As the pin O passes inward through the upper part of the groove Q it raises the dog R and passes on to its seat P. The bar L is provided with two grooves, Q, leading in opposite directions from 10 the said seat P, so that the operation will be the same in whichever direction the bar L may be moved.

To the ends of the shaft D, at the inner sides of the hangers B, are attached ratchet-wheels 15 S, with their teeth pointing in opposite directions. With the teeth of the ratchet-wheels S engage bent pawls T, which are placed upon the opposite sides of the shaft D, and are pivoted at their angles to the hangers B.

20 To the shanks of the pawls T are attached, or upon them are formed, laterally-projecting pins, which enter grooves U in the inner sides of the slide-bars L. The middle part of each groove U is inclined and the end parts are 25 horizontal and at different levels, as shown in Fig. 1. The grooves U of the two bars L are arranged with the upper part of each groove upon the same side of the shaft D as the lower part of the other groove. With this construction, when the bars L are moved in either direction the shank-pin of one pawl, T, will enter 30 the lower part of its groove U, and the engaging end of the said pawl will be held against its ratchet-wheel, while the shank-pin of the other pawl will enter the upper part of its groove, and its engaging end will be held away 35 from its ratchet-wheel. With this construction one or the other pawl, T, will always be in position to hold the shaft D from being turned 40 back by the strain of the brake-chain V, so that the brakes will be kept applied so long as the pressure is kept up from the car in front, and will thus be finally under the control of the engineer, who can keep the brakes applied 45 as long as necessary, it being intended that the pawls shall hold the ratchet-wheels, and through them the brakes, until just before the slide-bars are allowed to return to their central position.

50 One end of the chain V is attached to the shaft D in such a manner that it can be wound upon the said shaft D in either direction. The chain V passes over a guide-pulley, W, pivoted to a support attached to the base of 55 the car-frame. The other end of the chain V is connected with the lever or beam of the brake. An ordinary brake can be used; but I prefer to use a brake constructed to apply a brake-shoe to the opposite sides of each wheel 60 of the car. The brake is not shown in the drawings. With this construction, when the slide-bars L have been moved a little in the opposite direction from that in which the car is moving, the incline in the groove Q will allow 65 the pin O to be moved downward by the weight of the apparatus drawing the bearing-

block C downward and bringing the wheel E into contact with the wheel F, so that the movement of the said bars L will be continued by the advance of the car, and at the same 70 time winding the chain V upon the shaft D and applying the brake. When the pin O reaches the outer end of the groove Q the tension of the brake-chain V will cause the pin O to rise through the curve in the said groove Q, 75 throwing the wheel E out of contact with the wheel F, releasing the wheels I and leaving the bars L free to move back to a central position when released, the brake-shoes being held against the wheel by the pawl T until the 80 bars L have reached their central position and the shank-pin of the said pawl has entered the inclined middle part of the groove U, which releases the pawls and allows the brake-shoes to be withdrawn from the car-wheels by the 85 ordinary means. The ends of the slide-bars L, or bars or rods attached to them, are connected by cross-bars X, and extend at the ends of the car into such positions that the slide-bars of adjacent cars will not be brought into contact 90 by the ordinary yielding of the draw-heads when the cars are run together in coupling them.

To the inner sides of the end parts of the slide-bars L are attached, or upon them are 95 formed, rack-bars Y, into the teeth of which mesh the teeth of two gear-wheels, Z. The gear-wheels Z mesh into each other, are pivoted to the frame of the car, and the pivot or shaft a of one of the said wheels passes up to 100 the platform of the car and is provided with a hand-wheel, in the manner of an ordinary brake-shaft, so that a brakeman by turning the said shaft a can move the slide-bars L and bring the wheels E F into contact. 105

If desired, the cross-bars X can be placed at a little distance from the ends of the car, and can each have a bar, b, attached to its center, the said bar b having a bumper, c, attached to its outer end, and having a rack-bar, Y', attached to or formed upon it. In this case only 110 one gear-wheel Z will be needed, as shown in Fig. 8.

To each slide-bar L is attached the end of a short chain, d, the other end of which is attached to a spiral spring, e. The chain d passes between two guide-pulleys, h, attached to the car-frame, so that it will operate in the same way, in whichever direction the slide-bars L may move. The other end of the spiral spring 115 e is attached to a piston, f, working in an air-tight cylinder, g, firmly secured to the car-frame, or to some suitable support attached to the car-frame. With this construction, when the slide-bar L is moved in either direction, the 120 movement of the chain d will put the spring e under tension, and as the wheels E F come into contact the chain d and spring e will draw the piston f forward in the cylinder g against the air-pressure, so that the bars L, when released, will be drawn back to a central position 125 by the air-pressure upon the piston f and 130

the tension of the spring *e*; or, if desired, the same result can be secured by the use of pairs of springs attached to the slide-bars *L* and the car-frame, and arranged in opposite directions, so that one pair will be slack while the other is under tension.

In using the improvement, when the brake is to be applied the engineer, by means of a shaft, *a*, gear-wheel *Z*, and rack-bar *Y*, moves 10 the slide-bars *L* connected with the tender to the rearward to bring the wheels *E F* into contact, which causes the said bars to continue their rearward movement, applying the brake to the wheels of the tender. As the brake is 15 applied to the tender the forward movement of the said tender is checked, which allows the cars to press forward against it, which, in connection with the rearward movement of the bars *L*, brings the rear ends of the said 20 bars *L* into contact with the forward ends of the bars *L* of the forward car, and moves the said bars *L* so far to the rearward as to bring the wheels *E F* into contact and cause the bars *L* to be carried farther to the rearward 25 by the advance of the car and apply the brake to the said first car, and so on through the train, each forward car moving the bars *L* of the next car, so that the brakes will be applied successively and automatically to all the cars 30 of the train.

In case a car without my improvement should be placed in the train, a brakeman should be placed upon the car next in the rear of the said car to move the bars *L* at the proper time 35 by means of the shaft *a*, gear-wheel *Z*, and rack *Y*, when the brakes will be applied to that car, and successively to all the rear cars, in the manner hereinbefore described. The shaft *a* operated by the engineer should be 40 provided with a ratchet-wheel and pawl to prevent the bars *L* from being drawn so far forward as to withdraw the brakes before the proper time. As soon as the engineer releases the shaft *a* the bars *L* will be drawn forward

and the brakes withdrawn in the manner hereinbefore described. 45

In case of a backward movement of the train a brakeman in the caboose or car at the rear end of the train can apply the brakes to the whole train equally as well as the engineer 50 can when the train is moving forward.

Having thus described my invention, what I claim as new, and desire to secure by Letters Patent, is—

1. A car-brake constructed substantially as 55 herein shown and described, and consisting of the friction-wheels *E F*, the gear-wheels *H I*, the slide-bars *L*, having rack-bars *K* and grooves *Q U*, the sliding bearing-blocks *C*, and ratchet-wheels and pawls *S T*, as set forth. 60

2. In a car-brake, the combination, with the axle *G*, the car *A*, and the brake-chain *V*, of the sliding bearing-blocks *C*, the friction-wheels *E F*, the gear-wheels *H I*, and the slide-bars *L*, provided with rack-bars *K*, and having 65 grooves *Q*, substantially as herein shown and described, whereby the brakes will be applied by the advance of the cars, as set forth.

3. In a car-brake, the combination, with the shaft *D*, carrying the friction-wheel *E* and 70 brake-chain *V*, and the slide-bars *L*, having grooves *U*, of the ratchet-wheels *S*, and the pawls *T*, substantially as herein shown and described, whereby the said shaft and brake-chain are held in place when the friction-wheels 75 are thrown out of contact, as set forth.

4. In a car-brake, the combination, with the slide-bars *L* and the car *A*, of the chain *d*, the guide-pulleys *h*, the spring *e*, the piston *f*, and the cylinder *g*, substantially as herein shown 80 and described, whereby the said slide-bars are drawn back to a central position when released, as set forth.

WILLIAM C. SCHULTZE.
